BLOCK SIGNALING SYSTEM FOR
RAILWAYSCarl König, Vohwinkel-Hammerstein,
near Elberfeld, GermanyApplication November 29, 1930, Serial No. 499,001
In Germany November 29, 1929

1 Claim. (Cl. 246—81)

This invention relates to automatic block signaling systems for railways in which the train when leaving a block is caused to send two or more current impulses into the block signaling system, the first of said current impulses being used to close a contact in the circuit leading to the rearwardly positioned block signaling apparatus.

My invention consists essentially therein, that the second of said current impulses is caused to operate by way of these contacts, at the beginning of the rearwardly positioned block, signaling apparatus to indicate that the respective block is "free" and that the retarding and current limiting apparatus have been moved back into its initial position, thereby simultaneously again interrupting the circuit which had been closed by said first current impulse to the rearwardly positioned signaling apparatus by opening said contact. In this manner further current impulses will no more be able to affect the block signaling apparatus.

An example of a block signaling system according to my invention is shown in the accompanying drawing of which

Fig. 1 is a diagram showing the connection of two railway block stations which are in signaling connection with each other, the mechanism shown in the lower half of the figure being the retarding and current-limiting apparatus,

Figure 2 shows also the retarding and current-limiting apparatus, the movable members being, however, in another position,

Fig. 3 is a view similar to Fig. 2, showing the same parts in another position, and

Figs. 4 and 5 are views similar to the uppermost portion of Fig. 1 and show a railway car in two other positions relatively to the places where the current is drawn from the overhead line.

On the drawing, R denotes the track of an electric railway and O the overhead line which receives the current from the electric central station Z. The track is subdivided in the usual manner into individual blocking stations (I and II), each of which is provided with a block signaling apparatus S₁ or S₂, respectively. Each thereof is provided with a green lamp L_g for indicating that the line is clear, and with a red lamp L_r co-operating with the stopping signals. These optical signaling means may be combined with mechanical ones. I have abstained from showing in the drawing also mechanical signaling means (in connection with said optical ones) in that they do not constitute essential

parts of this invention. The said block signaling apparatus receives the current from the overhead line of the track, from which the current is tapped at the point J₁ or J₂, respectively, the current being then conducted according to the position of a switch N₁ or N₂ respectively, either across the pivot 14 of the switch arm, the contact, the switch arm U₁ or U₂, respectively, the contact piece 3 and the green control lamp C_g to the green signal lamp L_g, or across the pivot 14, the contact 16, and the control lamp C_r to the red signal lamp L_r. From both lamps the current flows back to the track through the wire 21 which is connected with the track R at the point 7, as shown.

When the switch N₁ or N₂, respectively, is in the first-mentioned position, as in the drawing, so as to supply the green lamp with current, the current can nevertheless be conducted also to the red lamp. That is effected by turning the switch lever U₁, or U₂, respectively, onto the contact piece 4, in which case the current passes from this contact piece across the control lamp C_r.

There appertains to each block signaling apparatus, besides the just described circuit a second circuit, with the aid of which the switch U₁ or U₂, respectively, is actuated. These second circuits of the individual block signaling apparatus are connected with one another by a wire 22, and also they receive the requisite current from the overhead wire O of the track. The current is drawn therefrom at the point J₁ or J₂, respectively, provided, that a railway car has established a connection between the overhead line and said point J₁ or J₂, respectively. In this case, the current passes across the contact piece 8 the electromagnet E₁ the wire 23, the solenoid coil M₁ and the wire 24 to the point 9 at the track. Near the contact piece 8 is provided a branch switch R₁ which is so designed that it branches off from the circuit located between the point J₁ or J₂, respectively, and the contact piece 8, a current, if the switch arm R₁ contacts with said contact piece 8. This part of the current then flows across the contacts 12, 10, f₁, f₂ and 11 to the rearwardly located blocking station, and in the same across the appertaining electromagnet E₂, the solenoid coil M₂, and the wire 27 to the point 9 at the track. In order to render it possible that a current flows through that branched-off circuit, it is necessary that the contact f₁, f₂ is closed. The construction and operation of this contact will be fully described hereinafter.

Drawing current from the overhead line O at the point J₁, or J₂, respectively, is possible, however, only if a car just running through the respective portion of the track establishes a connection between the line O and said point J₁, or J₂. In the example shown in Fig. 1 it is assumed that the cars T₁, T₂ and T₃ are provided with trolleys K₁, K₂, K₃, K₄, K₅ and K₆. Each car has two trolleys which are conductively connected with one another, whereby it is rendered possible that when one of the two trolleys pertaining to a car contacts with the current-carrying line O and the other trolley contacts with the line section in which the point J₁ or J₂ respectively, is located, the current can pass from the current carrying line O across the two trolleys to said point J₁ or J₂, respectively, as is the case in Fig. 5.

When, thus, a car runs past a block signaling station and its two trolleys contact successively with the line section containing the point J₁, or J₂, respectively, there will in that moment in which the first trolley, say K₁, contacts with said line section a current flow through the above described circuit, and this action will last as long as said trolley contacts with the said line section. Thereafter the flow of the current is interrupted, but is established anew when the other trolley arrives upon the section in which the point J₁, or J₂, respectively, is located. In order to bring about that interruption at the proper points of time it is necessary that the two trolleys of every car are more remote from one another than would correspond to the length of the line section containing the point J₁ or J₂, respectively. When a car has moved past the line portion with the point J₁ it gets into the range of the line section with the point J₂, and so on, as may be seen from Fig. 5. It is a matter of course that the number of line interrupting places may be chosen as best suited for the conditions of the individual tracks.

When a car runs through a block signaling station a plurality of current impulses, at least, however, two such ones, are sent into the circuit of the block signaling apparatus across the point J₁, or J₂, respectively, each of the two impulses, if provision for only two has been made, as in the constructional form illustrated in the drawing by way of example, taking its way across the wire 28, the contact piece 8, the electromagnet E₁, wire 23, the solenoid coil M₁, the wire 24, and the connecting point 9 of the track. Each rush of current excites the electromagnet, as well as the solenoid coil. The electromagnet attracts the armature A₁, or A₂, respectively, which is so connected with the switches R₁ and U₁, or R₂ and U₂, respectively, that when the armature A₁ or A₂, respectively, is being attracted by the appertaining electromagnet, the switch U₁, or U₂, respectively, contacts with the contact piece 4, whereby the red lamp is switched on, whereas the switch R₁, or R₂, respectively, contacts with the contact piece 12, whereby the sub-circuit containing the contact members 10, f₁, f₂, and 11 is closed, provided, that the position of the contact members f₁, f₂ is such that the current can pass through it.

Simultaneously with the electromagnet E₁ also the solenoid coil M₁ is excited whereby the core B₃ is drawn thereinto. The core is connected with the contact springs f₁, f₂ by mechanical means which are described in detail hereinafter, and the arrangement and combination of the parts concerned is such that, while

the contact f₁, f₂ is closed when the first current impulse ceases, it is again opened when the second current impulse ceases, but it is not actuated in any manner by current impulses which may follow those two.

The contact springs f₁, f₂ project forth from lever arms h₁ and h₂ and are insulated from the same, said arms being movably connected with one another and having the common fulcrum W. At the free end of each of said arms is a projection V₁, or V₂, respectively, which are directed towards one another and their length in this direction is such that when they contact with one another the contact between the springs f₁ and f₂ is interrupted, as in Fig. 1. The lever arm h₁ is provided with two noses n₁ and m₁ and the lever arm h₂ is provided with two noses n₂ and m₂. Opposite the first-mentioned two noses is a pawl a₁ having two noses p₁ and q₁ and being supported upon a pivot W₁, and opposite the other two noses is a pawl a₂ having two noses p₂ and q₂ and being also supported upon a pivot W₁. The noses n₁ and m₁ co-operate with the noses p₁ and q₁, and the noses n₂ and m₂ co-operate with the noses p₂ and q₂. The pawls a₁ and a₂ are hinged to a rod St which is firmly connected with the solenoid B₁ and is suspended from a helical tensile spring F₃, the strength of which is such that it can hold the solenoid core in its upper position when it is not subjected to the action of current passing through the appertaining coil.

Another helical tensile spring F₁ tends continually to hold the lever arm h₁ in its upper position (Fig. 1, station II, and Fig. 2). A third helical spring F₂ which is a compressive spring is arranged below the lever arm h₂ and tends continually to move it upwardly so as to keep the projection V₂ of this lever arm in contact with the projection V₁ of the lever arm h₁, as in the station II of Fig. 1. Finally, laterally from the spring F₁ is a helical tensile spring F₄ which is connected with the core B₂ of a solenoid M₂ that draws this core against, and presses it onto, the lever arm h₁ when the coil M is traversed by a current. Otherwise the spring F₄ holds the core B₂ remote from the arm h₁.

When the car T₁ is running on the track between two block signaling stations (I and II), the track portion concerned must be blocked in rearward direction. On the station I, therefore, the switch arm U₁ contacts with the contact piece 4, the switch arm R₁ with the contact piece 12, and the armature A₁ is attracted by the electromagnet E₁. On the station II the switch arm h₂ is in that position in which the projections V₁ and V₂ contact with one another as do also the noses m₁ and p₁. In this position of the parts the contact f₁, f₂ is open. While the car is running from the station I to the station II, the switch arm of this station contacts with the contact piece U₂ 3 so that the green lamp is switched on and the track portion concerned is announced as being clear. The switch arm R₂ is at this time out of contact with the contact piece 12 and the armature A₂ is kept attracted by the electromagnet E₂.

When the car reaches with its first brush K₁ the track portion in which the connecting point J₂ (that pertains to the station II) is located the solenoid M₁ of the station II is excited and the core B₁ is drawn thereinto whereby the rod St is moved downwardly and the pawls a₁ and a₂ are turned in such a direction that, as regards first the pawl a₁, the nose n₁ of the

lever h_1 can move past the nose p_1 of said pawl when said lever is turned upwardly under the pull of the spring F_1 , whereas the nose m_1 of the lever h_1 contacts with the nose q_1 of the said pawl, and is stopped thereby. The lever h_2 follows the lever h_1 under the pressure of the spring F_2 . The parts are then in the position shown in Fig. 3.

When then, thereafter, the brush K_1 of the car T_1 leaves the track portion in which the point J_2 is located, the solenoid becomes currentless and the spring F_3 draws the rod St and the core B_1 upwardly into their former position, and at the same time the pawls a_1 and a_2 are correspondingly turned, and as now the nose m_1 of the lever h_1 can move past the nose q_1 of the pawl a_1 the spring F_1 will lift the lever h_1 still further, but the lever h_2 cannot follow the lever h_1 because its nose n_2 is retained by the nose p_2 of the pawl a_2 . Owing to that moment of the levers h_1 and h_2 relatively to one another the contact f_1, f_2 will be closed, as shown at the right-hand end of Fig. 2.

While the car is running through the block signaling station II the brush K_2 of the car T_1 passes through the line portion containing the connecting point J_2 and a second current impulse flows from the overhead line O across the brushes K_1 and K_2 , the wire 29, the contact piece 8, the electromagnet E_1 , the wire 30, the solenoid M_1 and the wire 31 to the connecting point 9, at the track. As now said solenoid is again excited, it attracts the core B_1 , draws the rod St downwardly and turns the pawls a_1 and a_2 whereby it is rendered possible that the nose n_2 of the lever h_2 can move past the nose p_2 of the pawl a_2 so that this lever can now follow the lever h_1 until its nose m_2 contacts with the nose q_2 of the pawl a_2 and is stopped and retained by the same. In this position of the parts in question the contact springs f_1, f_2 are still open.

At the same time, however, a current branched off from said second rush of current flows across the contact piece 8, the switch arm R_2 , the wire 32, the contact piece 10, the contact springs f_1, f_2 , the contact piece 11, and the wire 22 rearwardly to the preceding station (I), in consequence whereof the electromagnet E_2 attracts the armature A_1 (on the station I) whereby the switch arm R_1 is drawn away from the contact piece 12 so that the sub-circuit of the station I is interrupted. Simultaneously therewith the armature A_1 turns the switch lever U_1 from the contact piece 4 to the contact piece 3 whereby the green lamp indicating that the track at the station I is free is switched on. Owing to the solenoid M_2 being excited simultaneously with the electromagnet E_2 the core B_2 of said solenoid is drawn thereto and its free end is thereby pressed onto the lever h_1 whereby also the lever h_2 is moved downwardly by the intermediary of the projections V_1 and V_2 of these levers, this movement being continued until the nose n_1 of the projection V_1 has arrived behind, i. e. below, the nose p_1 of the pawl a_1 .

When the second rush of current ceases, that is to say, when the brush K_2 of the car leaves the line portion in which the connecting point J_2 is located the solenoid M_1 becomes currentless,

so that the core B_1 of the same is pulled upwardly by the spring F_3 by the intermediary of the rod St , and the pawls a_1 and a_2 are also, therefore, turned back into their former position, or position of rest respectively. The nose m_2 of the lever h_2 can now move past the nose p_2 of the pawl a_2 so that the projection V_2 of the lever h_2 can contact with the projection V_1 of the lever h_1 , in consequence whereof the contact springs f_1, f_2 are opened.

The levers h_1 and h_2 have now reached that position in which they are nearest the solenoid M_2 and further impulses of current caused by further brushes passing away over the point J_2 cannot bring about any change in the position of said levers. Turning these latter back into their initial position can take place only when the car has reached the next blocking signaling station (III, not shown), the several movements of the parts concerned in this station (III) and in the preceding one (II) then taking place in exactly the same manner as has been described with respect to the stations I and II.

If the track is to be blocked without a car running through any part of it, that may be effected by shifting the switch arm N_1 (or N_2) from the contact piece 15 onto the contact piece 16 whereby the red lamps will be switched on independently of the other switching means that are automatically actuated in the described manner. The current flows then from one or the other of the connecting points 1 of the overhead line across the respective switch arm 14, the contact piece 16, the instrument C , the wire 32 or 31a, respectively, the lamp L_r and the wire 21, or 21a respectively, to the appertaining connecting point 7 of the track.

I claim:

An automatic block signaling system for electric railways, comprising, in combination with the conducting track, an overhead line divided into main sections and intermediate sections, each of which latter is located between two consecutive main sections and is insulated from them, back-signaling wires between the consecutive block stations, trolley cars having means adapted to produce two consecutive current impulses in the back-signaling wire concerned when running over the intermediate overhead line section concerned, electromagnetically actuated contact devices in the block stations, and conducting connections between said devices on the one hand and the main sections and the intermediate sections, as well as the track, on the other hand, said conducting connections forming circuits connected with one another by the back-signaling wires; said electromagnetically actuated contact devices comprising switching levers and contacts closed by means of the appertaining electromagnet by the first of said two consecutive current impulses and closing thereby the circuit for the electromagnet pertaining to the switching lever of the rearwardly located block station which in turn causes opening of the block station following it, and signaling means adapted to be electrically operated by the said switching levers in dependency of the said contacts, substantially as set forth.

CARL KÖNIG.
